UNITED STATES PATENT OFFICE.

WILBUR S. LEWIS, OF CLEVELAND, OHIO, ASSIGNOR TO THE S. LE MUR COMPANY, OF CLEVELAND, OHIO, A CORPORATION OF OHIO.

HAIR-WAVING CURLER ROD.

Application filed November 13, 1926. Serial No. 148,177.

My invention relates to curler rods, and relates particularly to hair curler rods employed in the art commonly known as "permanent waving".

5 In a prior application for patent, Serial No. 109,077, filed May 14, 1926, I disclosed a form of curler rod comprising a rod element and a tubular element telescoped over the rod, the two elements being removably 10 secured together and being relatively rotatable but being frictionally restrained from easy rotation by the elements being spring-pressed together in contacting portions thereof. Curler rods of this general 15 type are now in use and since, during a waving process a considerable number of such rods are in use at one time, strands of hair of a patient operated upon being wound upon each of such curler rods, it is highly im- 20 portant that the curler rods be made of very light material and the rod element of such curler rods is therefore commonly made of aluminum or aluminum alloy material, the tubular element therefor being made quite 25 thin and of brass, German silver, or the like.

I have found that the hair-treating materials employed in the form of a solution during the hair waving process, have a deleterious effect upon the contacting surfaces 30 of the aluminum rod and enclosing metallic tube, and since it is impracticable to employ other than dissimilar metals for the rod and tube, this deleterious effect which is accomplished by an electrolytic action between the 35 rod and tube acting as electrodes, and the hair-treating materials in solution acting as an electrolyte, is commonly had to a degree whereby relative rotation of the tube and rod may be prevented.

40 This action also sometimes progresses to such an extent that corrosion of one of the engaging surfaces, and the formation of a base material in contact with such surface, prevents removal of the tube from the rod, 45 which might otherwise permit cleaning of the corroded surfaces and removal of the base material.

50 My present invention, therefore, has for its object to prevent such undesirable amount of electrolytic action as will cause the contacting surfaces of the rod and tube to so adhere together as to restrict their relative rotation and their relative endwise movement during disassociation of the tube and 55 rod.

Another object of my invention is to lubricate the contacting surfaces of the tube and rod, whereby with a given spring pressure exerted between the tube and rod, there will always be approximately the same 60 amount of frictional resistance to rotation which may be practically predetermined.

Another object of my invention is to provide an improved curler rod comprising concentric telescoped portions between which 65 electrolytic action will be prevented or limited to a nonobjectionable amount, and which may be capable of being relatively rotated after successive hair waving operations.

70 Another object of my invention is to provide a hair curler having a pair of relatively rotatable concentric parts, having a lubricating means to ensure relative rotation between the parts, the lubricating means being 75 easily replaceable.

80 Other objects of my invention and the invention itself will become apparent from the following description of an embodiment of my invention, and in which description reference will be had to the accompanying drawings illustrating the said embodiment.

85 Referring to the drawings:

Fig. 1 shows a plan view of a curler rod embodying my invention, enlarged;

85 Fig. 2 is a similar view of the rod portion thereof per se.

Fig. 3 is a similar view of the tube portion thereof per se.

90 Fig. 4 is a transverse section taken on the line 4—4 of Fig. 1.

Fig. 5 is a longitudinal section taken on the line 5—5 of Fig. 1.

95 Fig. 6 shows a perspective view of a wick element of lubricant absorbent material employed in the embodiment illustrated in the foregoing figures.

100 Referring, now, to the different figures of drawing, in all of which like parts are designated by like reference characters, at 1 I show a rod which is split at 2 to form two outwardly bowed portions 3 and 4, the split portion of the rod extending for, perhaps, one quarter of the length of the rod, the exterior surface of the rod being annularly 105 grooved at 5 and 6, adjacent the ends of the rod. The end having the groove 5 is bifurcated by a slot 7 to form a tip to which a strand of hair may readily be secured by tying during the preparation of the hair 110

for the waving process. After the manner described in my co-pending application, Serial No. 87,777, filed Feb. 20, 1926, the other end of the rod, *per se*, is flattened, as shown at 8, to permit the operator to turn the rod by hand to tighten the hair, as will be well understood by reference to my aforesaid co-pending applications.

At 9 I show a collar tightly fitted upon the end of the rod 1, adjacent its flattened end 8, and between such flattened end of the groove 6, this collar forming a stop for the tube 10; when the tube 10 is telescoped over the rod 1, the tube 10 has an inwardly extending annular rib 11 adjacent one end and which end is slotted at 12, the slot 12 extending longitudinally medially of the tube from its end through its opposite walls to permit yielding of the two separated wall portions within the elastic limit of the resilient metallic material of which the tube is made. The tube 10 has its other end inturned slightly, as shown at 13. The inturned end of the tube 10 makes contact with the rod adjacent to its groove 5, but spaced therefrom slightly, and prevents contact between the inner walls of the tube and the rod 1 in other portions adjacent the inturned end 13 of the tube.

Within the slot 2, I place a wick of felt, or like lubricant absorbent material, shown at 14, the wick *per se* being illustrated in Fig. 6, and comprises a strip of felt, or the like, of a width preferably about the diameter of the rod 1 and of a length such that, after being impregnated with a lubricant such as vaseline or the like, it may be placed within the slot 2 between the outwardly bowed portions 3 and 4 of the rod, and may make contact by its edge portions 15 with the inner walls of the tube. The lubricant containing pad 14 being first inserted into the slot 2 of the rod 1, the tube 10 is then telescoped over the rod, as illustrated in Fig. 1, to "home" position, wherein the inwardly extending rib 11 is projected within the annular groove 6, the rib being held within the groove 6 by the inherent resiliency of the metallic material of the tube, the bifurcated arcuate portions 16 and 17 of the tube tending to retain their normal unstressed form.

The presence of the lubricant contained within the rod keeps the contacting portions of the rod and tube coated with a film of lubricant, whereby electrolytic action between the tube and rod is effectually retarded, if not entirely prevented. The exterior surface of the rod may be preliminarily lubricated by rubbing with a cloth con-

taining lubricant before assembling the rod within the tube, or dependence may be placed upon the lubricant contained by the pad 14. I find that the lubricant contained in the pad is sufficient to prevent the deleterious effect of electrolytic action in the presence of a borax solution or other hair-treating material in solution, between the rod and tube, even where the rod and tube are of metals having widely different electrolytic potential values.

Having thus described my invention in a specific embodiment, I am aware that numerous and extensive departures may be made from the embodiment herein illustrated and described but without departing from the spirit of my invention.

I claim:

1. In a curler rod of the class described, the combination with a pair of concentric relatively rotatable rod elements, to one of which a strand of hair is adapted to be secured, and around the other of which a strand of hair may be wound, a recess within one of the said elements, and a pad of lubricant absorbent material disposed within the recess, said pad adapted to communicate lubricant to contacting portions of the said elements.

2. In a curler rod of the class described, the combination with an outer tube, a rod within the tube and projecting at either end therefrom, said rod having a slotted portion disposed within the tube and a lubricant pad disposed within the slot, said rod having a slot-separated portion bearing against the inner wall of the tube, said pad lubricating the bearing between the said rod contacting portion and the tube.

3. In a curler rod of the class described, the combination with an outer tube, a rod telescoped through the tube having a handle at one end and its other end adapted to be secured to a strand of hair, a lubricant containing pad disposed within the tube adapted to communicate lubricant to the contacting surfaces of the tube and rod.

4. In a curler rod of the class described, the combination with an outer tube, a rod telescoped through the tube having a handle at one end and its other end adapted to be secured to a strand of hair, a lubricant containing pad disposed within the tube adapted to communicate lubricant to the contacting surfaces of the tube and rod, said rod and tube making spring pressed frictional engagement each with the other.

In testimony whereof I hereunto affix my signature this 27 day of October, 1926.

WILBUR S. LEWIS.
